(57) **CLAIM**

The ornamental design for a lollipop candy mold, as shown and described.

DESCRIPTION

FIG. 1 is a top perspective view of a lollipop candy mold showing the new design;

FIG. 2 is a bottom perspective view thereof;

FIG. 3 is a front side elevation view thereof;

FIG. 4 is a rear side elevation view thereof;

FIG. 5 is a left side elevation view thereof (the right side elevation view of the lollipop candy mold is a mirror image of the view shown in FIG. 5);

FIG. 6 is a top plan view thereof; and,

FIG. 7 is a bottom plan view thereof.

The dash-dash type broken lines shown in the drawing views are included for the purpose of showing environmental subject matter and form no part of the claimed design. The dash-dot-dash type broken lines on the interior and exterior bottom of the claimed design show boundaries of the claimed design and form no part of the claimed design. The remaining dash-dot-dash type broken lines behind brackets show break lines and the appearance of any portion of the article between the break lines form no part of the claimed design.
